**STAPLE STRIP ROTARY BRUSH AND METHOD
OF MAKING**

Niels E. Nielsen, Summit, N. J., assignor to Newark Brush Company, Kenilworth, N. J., a corporation of New Jersey

Application January 13, 1954, Serial No. 403,728

7 Claims. (Cl. 15—198)

This invention relates to a rotary brush made up of bristles of suitable material such as relatively fine iron wire which are mounted by means of staples on a relatively narrow strip of metal such as steel that has holes punched or drilled therein in proper spaced relation and then this strip is rolled up into a circle and the ends welded together after which the ring with the brush assembly thereon is mounted on and between a pair of circular plates.

It is the object of my present invention to provide a new and improved brush construction that can be economically manufactured and one that will give satisfactory service and operation.

In the drawings:

Figure 1 is a plan view of one of the disc type support plates.

Figure 2 is a plan view of a strip on which the bristles are initially mounted.

Figure 3 is a view of the strip shown in Figure 2 but with the holes therein properly spaced to receive the brush units, one of which is illustrated on the strip.

Figure 4 is a section on the line 4—4 of Figure 3.

Figure 5 is a side view of the strip showing three of the brush units mounted thereon.

Figure 6 is a view showing one of the steps in the assembly operation.

Figure 7 is a view similar to Figure 6 but showing a further step in the assembly operation.

Figure 8 shows a further step in the process of assembly across the line 8—8 of Figure 1.

Figure 9 is a view on the line 9—9 of Figure 1 after the brush material B has been assembled as shown in Figure 8.

Figure 10 shows a complete assembled view of the greater portion of the brush.

Figure 11 shows a view similar to Figure 10 but showing a slightly modified form of construction.

Figure 12 is a view on the line 12—12 of Figure 11.

Figure 13 is a view on the line 13—13 of Figure 11.

In the various views wherein like numbers refer to corresponding parts, 1 and 2 are the two plates used for supporting the brush assembly. Plate 1 has an annular shoulder 3 forming the principal support for the brush assembly. Plate 2 has a relatively narrow shoulder 4 which gives additional strength to the shoulder 3 for rigidly supporting the brush assembly. Each of the plates 1 and 2 has inwardly projecting fingers 5 to which reference will be further made. A strip S of suitable material preferably of steel is provided with holes 6 having a spacing 7 to receive staples 8 that receive the bristles B. The staples 8 have their ends 9 bent toward each other over the strip S as clearly shown in Figure 5. I prefer to punch or drill the holes 6 in the strip S but staples may be forced directly through the strip. In either case after the bristles or brush material have been fastened to the strip S the same is rolled up so that the opposite ends come together where they are welded. Then the

2

assembled rolled up strip is placed between the two plates 1 and 2 as shown in Figure 6 and preferably welded to at least plate 1 and the plates 1 and 2 are then brought together so that their central portions come into contact 5 as shown in Figure 7, at which time they are spot welded together as shown at 10 in Figure 10. Then the plate flanges 11 and 12 are forced into final position as shown in Figures 8 and 9 whereby the fingers 5 arranged in staggered relationship on the two plate flanges 11 and 12 are forced between the bristles as shown in Figures 8 and 9.

Figure 11 is the same as Figure 10 except for safety lock fingers 13 which are spaced radially near the central mounting hole 14 in the two plates. Here again as in 15 my co-pending application entitled "Staple Plate Rotary Brush" the fingers 13 are positioned so that when the plates are forced together as shown in Figures 12 and 13 the fingers having a tapered side will engage the top part of the staples 8 thereby further assuring a safety lock 20 of the strip in the mounting plates each of which has holes 15 positioned in the two discs so as to give the proper alignment positions for the fingers 5 and 13.

From the foregoing it will be seen that I have provided 25 a new and improved form of rotary brush.

Having thus described my invention, what I claim is:

1. A rotary brush of the character described having a pair of disc shaped plates of substantially the same diameter, one plate having an inwardly projecting circular shoulder portion radially spaced a substantial distance 30 from its outer rim and forming a principal brush support, a relatively narrow strip of strong material having groups of staples carrying brush material fastened thereto, said strip being in circular form and fitted onto said shoulder portion support, the other plate having a narrow shoulder portion support, each plate having fingers which project into the brush material on the final assembly of the brush structure.

2. A rotary brush as set forth in claim 1 further defined 40 in that said strip is of flat metal having holes properly spaced therein to receive the staples of the brush material units to form a continuous brush surface.

3. A rotary brush as set forth in claim 1 further defined 45 in that said strip is of flat metal having holes properly spaced therein to receive the staples of the brush material units to form a continuous brush surface when the strip is rolled up and its ends welded together for placement on said shoulder and further defined in that the metal strip is welded to said shoulder to fix it securely to the shoulder.

4. The process of making a rotary brush which consists in forming a pair of circular plates with projecting fingers and mounting holes centrally located in the plates, one of the plates having a centrally located shoulder with 55 its mounting hole therein, taking a relatively narrow flat strip of metal and stapling thereto in close relationship a plurality of brush units, coiling up the strip and welding its ends together and to said shoulder and then applying the other plate and welding it to the shoulder plate and finally pressing the finger carrying portions of the plates 60 toward each other and forcing said fingers into the brush material, the brush material extending a substantial distance beyond the outer periphery of said plates.

5. A rotary brush as set forth in claim 1 further defined 65 in that safety fingers are provided on each plate and these are located so as to be forced into the brush material directly over and in contact with a staple.

6. A rotary brush as set forth in claim 1 further defined 70 in that when the final assembly operation is performed, the outer rims of the two plates are in substantial parallel relationship.

7. A rotary brush of the type described having a pair

of side plates, each plate having an inwardly projecting circular shoulder with the outer parts of the shoulder in the same cylindrical surface, the shoulder on one plate preferably projecting laterally farther than the shoulder on the other plate, a relatively narrow strip of strong metal having groups of staples carrying brush material fastened to the strip, said strip being in circular form and fitted onto at least the shoulder having the greater width and anchored thereto, means for fastening the

central portions of said plates securely together, each plate having fingers which go into the brush material.
